US00D781525S

(12) United States Design Patent (10) Patent No.: US D781,525 S
(45) Date of Patent: * Mar. 21, 2017

(54) PET TREAT

(71) Applicant: Spectrum Brands, Inc., Middleton, WI (US)

(72) Inventor: Marc Kreamer, Delray Beach, FL (US)

(73) Assignee: Spectrum Brands, Inc., Middleton, WI (US)

() Term: 15 Years

(21) Appl. No.: 29/549,670

(22) Filed: Dec. 28, 2015

(51) LOC (10) Cl. 01-01

(52) U.S. Cl.

USPC D1/106; D1/102; D30/160

(58) Field of Classification Search

USPC D1/100-130, 199; 426/5, 76, 87, 92, 94, 426/95, 99, 101, 103, 104, 108, 134, 426/138-139, 143, 144, 279, 282, 283, 426/391, 514, 549, 559, 560, 660, 808; D9/439, 669; D24/130; D6/597, 598, D6/601; D21/488-490, 493, 680; D23/366, 386, 415; 239/44; D8/83; D30/160
